UNITED STATES PATENT OFFICE.

ANDREW J. COPPOCK, OF DETROIT, MICHIGAN.

AUXILIARY CHARGE-FORMING DEVICE.

Application filed March 18, 1925. Serial No. 16,284.

This invention relates to auxiliary charge forming devices for internal combustion engines, and the object of the invention is to provide a means for adding water in the 5 form of steam and air to the intake manifold of an internal combustion engine operating in conjunction with the usual carburetor. The features of the invention are involved in a construction whereby water is 10 fed to a tube lying within the exhaust conduit of an internal combustion engine whereby it is heated, and in the means for causing the water to enter the device through a tube centrally disposed of the heated tube and 15 the vapor discharged from the forward end of the heated tube into the intake manifold.

Further features of the invention are involved in the control system whereby either steam or air or both may be discharged to 20 the intake manifold between the carburetor and the engine cylinders.

These and other objects and the several novel features of the invention are herein-after more fully described and claimed, and 25 the preferred form of construction of a device embodying my invention is shown in the accompanying drawings in which—

Fig. 1 is a view of an internal combustion engine with which my auxiliary charge 30 forming device has been incorporated.

Fig. 2 is an enlarged sectional view of the manifold showing my improved features more in detail.

Fig. 3 is a horizontal section of the control 35 valve mechanism taken on line 3—3 of Fig. 1.

Fig. 4 is a section through the plug by means of which the device is supported in the exhaust manifold taken on line 4—4 of Fig. 2.

Fig. 5 is a section through the device for taking water from the water jacket of the engine taken on line 5—5 of Fig. 1.

In Fig. 1 is shown an internal combustion 45 engine 1 which has the usual intake manifold 2 and the usual carburetor 3 attached thereto and also is provided with the ordinary exhaust manifold 4. A valve structure is indicated at 5 which is shown in detail in Fig. 3 and consists of a conduit 6 having at one end an air line 7 opening thereto. This air line 7 and the conduit 6 are preferably on the engine side of the instrument board indicated at 8 in Fig. 1 and 50 the air line leads downward to a distance from the operator's seat of the usual auto-

mobile as shown in Fig. 1 so that the noise of inrushing air is not observable. This valve structure 5 also has a control valve 9 for closing the conduit 6 to the air inlet line 7. There is also at the opposite end of the conduit 6 a valve 10 engaging a seat 11 to which the water line 12 opens. This valve controls the flow of water into the conduit 6. The conduit 12, as shown in Fig. 1, leads 60 to a plug 13 secured on the water jacket as shown in Fig. 5. The plug 13 consists of an outer case 14 having a threaded stem 15 extending into the water jacket space 17 of the engine casing and inside of the member 14 is a screen 18 to prevent particles of dirt or scale passing to the valve mechanism 5. Threaded in the member 14 is a flange nut 19 centrally apertured and internally threaded to receive the elbow 20 with which the line 12 is connected. Connected to the conduit 6 shown in Fig. 3 is a tube 21 which is connected with the plug 22 attached to the exhaust manifold 4. This plug 22 has a small tube 23 therein which is supported 65 by the connector 24 shown in Figs. 2 and 4 threaded on the external end to receive a nut 25 by means of which the line 21 is sealed to the open end of the tube 23. This member 24 is supported in a hollow nut 26 70 threaded in the outer case 27 of the member 22, which outer casing is threaded into the exhaust manifold 4 as shown in Figs. 2 and 4. This member 27 has an internal annular rib 28 and a pipe 29 has an outer open end 75 extending into the member 27 and the edge of the tube is flared to engage back of the rib 28. The member 26 at its inner end is coned to engage in the open end of the tube 29 seating thereon and holding the same in place. The opposite end of this tube 29 is closed as indicated in Fig. 2 and the inner small tube 23 is coiled within the tube 29 as shown in Fig. 2 and extends to very close 80 to the closed end of the tube 29 so that any fluid entering the central tube 23 is discharged into the outer tube 29 at the said closed end and may flow backward to the member 22. This member 22 as shown in Fig. 4 has in the side thereof an elbow 30 85 threaded into the side of the member 27 and extending through the opening to the chamber within the member 26. To this elbow is connected the tube 31 which has the elbow 32 at the opposite end opening into the intake manifold 2 as indicated in Fig. 2. As 90 shown in Fig. 2 a check valve 40 may be 95

100

105

110

provided opening into the chamber within the member 26 which is adapted to open in case a pressure is developed in the tube 29 which might be caused by water standing 5 in the heated tube 29 after the engine has been stopped. In this case the check valve 40 acts as a safety valve and allows the steam to blow off from the tube 29 but the check valve 40 normally remains closed.

- 10 It is to be noted that the tube 29 as well as the tube 23 can be removed from the manifold by unscrewing the member 22 therefrom which enables the entire device to be withdrawn from the exhaust manifold. 15 While the tubes 23 and 29 and member 22 are shown mounted in the exhaust manifold they may be mounted in the exhaust pipe leading from the exhaust manifold to the muffler as sufficient heat is developed in this 20 exhaust pipe to produce the desired result.

In the operation of the device and during the engine operation there is produced a suction on the line 23 and thence to the line 21 and to the conduit 6. This suction is 25 produced by movement of the pistons of the engine which tend to produce a partial vacuum in the cylinders which is transmitted through the line 31 to the interior of the tube 29 and thence to the tube 23. By opening 30 the valve 9 a greater or less amount of atmospheric air may be fed to the tube 31 and heated while passing through the tubes 23 and 29. This heated air is applied to the intake manifold at the point 32 and tends to vaporize the hydrocarbon charge 35 supplied by the carburetor in the usual way as will be readily understood.

Experience has proven that a slight amount of moisture in the charge for an 40 internal combustion engine adds to the efficiency of the charge and I have provided this means of adding steam to the charge. This is accomplished by the opening of the valve 10 by means of which the suction of 45 the engine is applied to the line 12 connected with the water jacket as heretofore described so that the water flow into the conduit 6, through the tube 21 to the line 23 and thence into the outer tube 29 at its inner end. This 50 water must then pass to the line 31 and in passing through the conduit 29 is heated to a degree to produce steam in the usual manner. This steam is drawing through the tube 31 by suction and is discharged in the 55 inflowing hydrocarbon fuel charge at the

point 32 so that additional water is continuously drawn through the device to maintain a flow through the conduits 29 and 31.

Both air and water may be supplied to the line 21 by opening both the valves 9 and 10 and in this manner produces excellent results but either valve may be opened or both may be opened depending on the desired result. By opening the water valve 10 only, considerable steam can be supplied to the engine which tends to eliminate carbon deposits in the cylinder head and on the spark plugs but oftentimes the atmosphere is sufficiently moist and in that case the valve 10 may be closed and only the air valve opened to admit an additional heated air charge to the inflowing charge formed by the carburetor. The features of the invention are involved in the control device as shown in Fig. 3 and the device shown more particularly in detail 75 in the exhaust manifold in Figs. 2 and 4 which includes the two tubes 29 and 23 and the discharge tube 31 therefor.

From the foregoing description it becomes evident that the device is very simple and efficient in operation, is composed of few parts and is of consequent low manufacturing cost and provides a device which accomplishes the objects described.

Having thus fully described my invention, 85 its utility and mode of operation, what I claim and desire to secure by Letters Patent of the United States is—

An auxiliary charge forming device for internal combustion engines having a carburetor, an intake manifold and an exhaust manifold, consisting of a tube opening at one end to the intake manifold between the carburetor and cylinders, a second tube extending into the exhaust manifold longitudinally thereof from one end and having a closed end adjacent the discharge end of the manifold and the first tube opening to the second tube outside the exhaust manifold, a third tube extending into the second tube and having an open end adjacent the closed end of the second tube, a valve controlled conduit connecting the third tube to the water jacket of the engine, and a valve controlled conduit opening to atmosphere and leading to said third tube through the first named valve controlled conduit.

In testimony whereof I sign this specification.

ANDREW J. COPPOCK.
